Patented June 22, 1920.

FIG. 1.

FIG. 2.

FIG. 3.

FIG. 4.

Inventor:
Harry R. Hirst
By his Attorney
F. DeWitt Goodwin

UNITED STATES PATENT OFFICE.

HARRY R. HIRST, OF TRENTON, NEW JERSEY.

REPAIR-TOOL FOR TIRES.

1,343,971.

Specification of Letters Patent. Patented June 22, 1920.

Application filed March 20, 1919. Serial No. 283,871.

To all whom it may concern:

Be it known that I, HARRY R. HIRST, a citizen of the United States, residing at Trenton, in the county of Mercer and State 5 of New Jersey, have invented certain new and useful Improvements in Repair-Tools for Tires, of which the following is a specification.

My invention relates to a repair tool for 10 tires, particularly for repairing punctured pneumatic tires, by inserting in the aperture of the tire a number of elastic bands to form a plug which will seal the puncture.

The object of my invention is to provide 15 a tool which is simple in construction and operation and which can be manufactured at a very low cost; a further object of my invention is to construct a tool having a self locking pivoted member which will hold the 20 elastic bands stretched and in a position ready for use without the necessity of holding the pivoted member, by hand, from rotating or by providing a locking device or 25 releasing trigger, to prevent it from rotating, which result is accomplished by so arranging 30 the parts that the stretched bands will hold the pivoted member against a stop, by exerting a strain in a line back of the pivot point of the pivoted member.

And a still further object of my invention 35 is to provide the needle with side members between which the pivoted member is guided and by forming the side members with rounded corners which will allow the elastic 40 bands to freely pass over the pivot point of the pivoted member, both at the time the bands are being looped over the pivoted member and at the time the latter is rotated to discharge the bands.

Referring to the accompanying drawings: 45 Figure 1, is a side elevation of my improved tool for repairing tires; Fig. 2, is an edge view of the device shown in Fig. 1; Fig. 3, is a view similar to Fig. 1, showing the elastic bands in place upon the tool; and Fig. 4, is a view similar to Fig. 3 showing the tool inserted in a tire and the pivoted member slightly turned and about to free itself of 50 the elastic bands.

In the accompanying drawing in which like reference characters refer to like parts, 1 represents the needle, provided with an open slot 2, at its free end, to receive one portion 55 of the elastic bands. The opposite end of the needle is provided with a loop, forming an eye 3, by turning the wire, of which the

needle is formed back upon itself, thus forming side members 4 and 5 and a pivot-shaft 6 extending at right-angles with the length of the needle. Upon the shaft 6 is loosely 60 mounted the pivoted member 8. The side members 4 and 5 of the needle embrace the pivoted member 8 and form guides for holding the latter in a plane parallel with the length of the needle. 65

The pivoted member 8 consists of a flat plate having a central aperture formed therein through which the pivot-shaft 6 passes. The member 8 is provided with a projection forming a stop 10 which takes 70 against the needle 1 and limits the movement of the member 8 in one direction. The said member 8 is also provided with a notch 12 adapted to receive the elastic bands 14. The bands 14 are looped over the member 75 8, passed through the slot 2, formed in the free end of the needle, and again looped over the member 8, as shown in Fig. 3.

The pivoted member 8 has the notch 12 so positioned therein that the elastic bands 80 14 will hold the stop 10 against the needle 1 and thus hold the member 8 in the position shown in Figs. 1 and 3. The notch 12, formed in the member 8, is located out of alignment with the slotted end of the needle 85 and the pivot-shaft 6, so that the pressure of the elastic bands will hold the pivoted member 8 in the position shown in Fig. 3.

The pivoted member 8 forms a substantial handle for forcing the needle, with the elastic bands thereon, into the punctured tire 15. By pressing the finger against one side of the member 8, the latter may be turned upon the pivot-shaft 6, as shown in Fig. 4, and the contraction of the elastic bands will then 90 turn the member 8 into the position shown in dotted lines Fig. 4 and the bands will free themselves from the member 8. The shoulders 7 between the side members 4 and 5 and the pivot-shaft 6 are rounded so that 100 the elastic bands will freely pass over them, thus permitting the bands 14 to assume a straight line between the notch 12 formed in the pivoted member 8 and the free end of the needle, as shown in Fig. 3. The said 105 rounded shoulders 7 allow the bands 14 to readily slide over the pivot point of the member 8.

Having thus described my invention I claim and desire to secure by Letters Patent; 110

1. A needle having band engaging means in one end thereof, a member pivoted in the

opposite end of the needle and having a stop formed thereon adapted to engage the needle, said pivoted member having a notch formed therein to receive said band and 5 extend the latter in a line passing the pivot point of the pivoted member on the same side of the needle that the stop engages the needle.

2. A needle having an elastic band receiving opening therein, a member pivoted to the needle, a stop formed upon said member adapted to engage the needle and prevent the turning of the said member in one direction, said pivoted member having means 10 thereon for receiving said elastic band adapted to extend between the end of the

needle having the receiving opening formed therein and the said receiving means upon the pivoted member and hold the stop upon said member in engagement with the needle and said pivoted member being adapted to be rotated and move the said receiving means thereon over the pivot point of the said member and discharge the elastic band therefrom.

In testimony whereof I affix my signature in the presence of two witnesses.

HARRY R. HIRST.
